UNITED STATES PATENT OFFICE.

ISADOR LADOFF, OF CLEVELAND, OHIO, ASSIGNOR OF THIRTY ONE-HUNDREDTHS TO PHILIP C. PECK, OF NEW YORK, N. Y.

ELECTRODE OR PENCIL FOR ARC-LIGHTS.

No. 908,428.

Specification of Letters Patent.

Patented Jan. 12, 1909.

Application filed May 27, 1908. Serial No. 435,216.

To all whom it may concern:

Be it known that I, ISADOR LADOFF, a citizen of the United States, and a resident of the city of Cleveland, in the county of Cuyahoga and State of Ohio, have invented certain new and useful Improvements in Electrodes or Pencils for the Arc-Light, of which the following is a specification, reference being had to the accompanying drawings.

10 My present invention relates more particularly to a positive "upper" pencil or anode, and especially in the combination thereof with a negative "lower" pencil or cathode consisting of, or preponderantly comprising, titanic and ferric material.

15 The object of my present invention is to supply, in combination with such negative pencil, an upper or positive pencil of such construction, composition, and resulting behavior as to facilitate, under all conditions, the starting of the arc, and also increase its length and candle power, without undue expenditure of energy, or rapidity of consumption. I attain this, and other desirable objects, by constituting the body of said upper positive pencil or electrode of carbon having a central longitudinal core or axis of iron, or ferric material.

20 The construction of my said improved upper is shown in the accompanying drawing, in which—

25 Figure 1 is a longitudinal central section of the pencil, Fig. 2 a cross section on the line 2—2 of Fig. 1, and Fig. 3 an elevation showing my novel combination of my said upper with said lower titanic and ferric pencil.

30 My said upper may be constructed in any convenient manner;—the carbon pencil being first produced as usual, may be bored and the iron core inserted, or the carbon constituent may be molded in plastic state around the iron core and then sintered, the method of construction constituting no part of my present invention.

35 The relative proportion of the total carbon or graphite to total iron or ferric material appears to be important. I have found that when iron core is thus used with carbon the best results are attained where the diameter of the iron core is $\frac{3}{8}$ " and that of the entire pencil $1\frac{1}{4}$ " and that when iron core is used with graphite the best diameter of core is $\frac{1}{4}$ " and of entire pencil 1".

40 My said iron cored carbon, when used as

positive or anode in combination with a 55 lower or cathode comprising ferric and titanic material, as for instance the pencil of my Patent No. 840,634, dated January 8, 1907, or pencils comprising oxid of titanium and iron, as per my pending application, Serial No. 213,065 filed June 18, 1904, as a division of my application, Serial No. 183,528, filed December 2, 1903 has proved of advantage, my said upper in such case facilitating the starting of the arc, increasing its length, 60 enriching it in volatile material, increasing its candle power, etc., and accomplishing all without increased expenditure of electrical energy as compared with other uppers or anodes known to me.

70 The presence of the iron in the form of a core as described, increases materially the life of the carbon or graphite pencil containing it, as compared with that of similar pencils, either without such core or combined 75 with iron or other forms, and the location of the iron constituent thus in bulk located within and surrounded by the carbon, is also of importance, in that it minimizes oxidation of the ferric constituent, which if applied externally to the carbon as in the form of a tube, I have found on several accounts obnoxious, if not prohibitive.

75 The core may be composed of a compound of iron or ferric material instead of the metal in elemental form, though I have found the latter preferable; also the body of the pencil may be composed of various forms of carbon, as for instance graphite, as above referred to, though I have found carbon per 90 se preferable.

80 Referring to Fig. 3 of the drawings, A indicates an arc lamp of usual form and provided with the usual feed devices, B my said positive upper pencil or anode of carbon having the aforesaid central longitudinal core or axis of iron or ferric material, C the negative lower pencil or cathode comprising ferric and titanic materials.

85 The pencils are of course to be understood as being connected as usual in circuit with a source of electrical energy, not shown.

90 What I claim as new and desire to secure by Letters Patent is the following, viz:—

95 1. In an apparatus for producing the arc light the combination of a positive pencil or electrode composed of carbon surrounding an axially disposed core of iron and a negative

- pencil or electrode comprising ferric and titanic material.
2. In an apparatus for producing the arc light the combination of a positive pencil or electrode composed of carbon surrounding an axially disposed core of iron and a negative pencil or electrode composed preponderatingly of ferric and titanic material.
3. In an apparatus for producing the arc light the combination of a positive pencil or electrode composed of graphite surrounding an axially disposed core of iron and a negative pencil or electrode comprising ferric and titanic material.
4. In an apparatus for producing the arc light the combination of a positive pencil or electrode composed of graphite surrounding an axially disposed core of iron and a negative pencil or electrode composed preponderatingly of ferric and titanic material.
5. In an apparatus for producing the arc light the combination of a positive pencil or electrode composed of carbon surrounding an axially disposed core of ferric material and a negative pencil or electrode composed of ferric and titanic material.
- negative pencil or electrode comprising ferric and titanic material.
6. In an apparatus for producing the arc light the combination of a positive pencil or electrode composed of carbon surrounding an axially disposed core of ferric material and a negative pencil or electrode composed preponderatingly of ferric and titanic material.
7. In an apparatus for producing the arc light the combination of a positive pencil or electrode composed of graphite surrounding an axially disposed core of ferric material and a negative pencil or electrode comprising ferric and titanic material.
8. In an apparatus for producing the arc light the combination of a positive pencil or electrode composed of graphite surrounding an axially disposed core of ferric material and a negative pencil or electrode composed preponderatingly of ferric and titanic material.

ISADOR LADOFF.
